UNITED STATES PATENT OFFICE.

GEORGE C. LASARES, OF SPRINGFIELD, MASSACHUSETTS.

TOY GUN OF THE MAGAZINE TYPE.

1,135,703.

Specification of Letters Patent. Patented Apr. 13, 1915.

Application filed April 9, 1914. Serial No. 830,658.

To all whom it may concern:

Be it known that I, GEORGE C. LASARES, a citizen of the United States of America, residing at Springfield, in the county of 5 Hampden and State of Massachusetts, have invented new and useful Improvements in Toy Guns of the Magazine Type, of which the following is a specification.

This invention relates to improvements in 10 toy guns for shooting small spherical objects either of light or heavy material.

An object of the invention is to provide a device that can be readily operated or set to permit one of the projectiles to automatically 15 pass or fall from the magazine chamber into the barrel.

Broadly, the invention comprises a magazine chamber that is located immediately above the barrel and having an opening 20 communicating between the two at the forward end of the magazine chamber, an expelling piston located in the barrel and normally propelled forward by means of a compression spring, means comprising a 25 handle for setting or drawing back the propelling piston into a cocked position to lock the piston with the spring under compression, and a trigger to release the expelling piston and permit the stored energy in 30 the spring to exert its force to drive the piston forward.

Further, the invention comprises a temporary retaining receptacle to retain the projectiles in a stationary position prior to the 35 firing of the gun.

Referring to the drawings: Figure 1 is an outline view of the complete gun showing the lever for cocking the gun in its closed or rearward position. Fig. 2 is a vertical 40 longitudinal sectional view through the axis of the barrel showing the interior construction of the operative parts with the piston in its forward position after a projectile has been discharged, and, indicated in dotted 45 line position, is the handle mechanism for drawing the piston rearward into a cocked position. Fig. 3 is a transverse sectional view on the line 3—3 of Fig. 2. Fig. 4 is a detail vertical sectional view of the forward 50 end of the magazine and the adjacent portion of the barrel and showing the piston in a retracted position with the expelling spring under compression and illustrating the elastic tongue receptacle for temporarily 55 receiving a projectile after the same

passes from the magazine chamber to the barrel.

Referring to the drawings in detail, 1 designates the barrel, 2 the stock or handle portion of the toy gun, and 3 the magazine 60 chamber. This chamber is located above the rear portion of the barrel and extends rearwardly to the stock to which it is attached. It is permanently closed at its forward end by means of a cap 4. Access to 65 the interior of the magazine is obtained by removing the block or plug 5 for inserting the spherical projectiles 6 therein. It will be noticed that the magazine chamber is arranged in an inclined position so that the 70 projectiles normally roll forward toward the openings 7 and 8 which register with each other and whereby the projectiles may pass from the magazine to the barrel as indicated in Fig. 4. 75

9 designates a spacing block located between the forward end of the stock 2 and the rear end of the magazine to maintain the magazine in an inclined position.

10 designates a piston that is attached to a 80 rod 11 by means of the screw-threads 12.

13 designates two pins or stops against which the compression spring 14 at one end bears, the forward end of the compression spring engaging the rear side of the piston 85 10. 14

The rod 11 is formed, at its rear end, with a downwardly extending projection 15. This projection is engaged by the forward end 16' of the setting lever 16 that is pivotally connected, as shown at 17, to the inclosing casing 18 and extends rearwardly as indicated where it engages the underside of the stock 2. 90

20 designates a projection that is made 95 tapering as indicated at 21, the purpose of which is to automatically lock the handle 16 to the stock after the piston is drawn back into a cocked position.

22 designates the trigger that is formed 100 with a catch or pawl portion 23. The trigger is pivoted in the casing 18 at 24 and is normally actuated to move the locking pawl 23 upward by means of the spring 25 whereby when the lever 16 is moved into the 105 dotted line position the downwardly projecting portion 15 on the rod 11 would be automatically caught behind the pawl 23 and held in a locked position. During this operation the foremost projectile 26 will fall 110

downward through the openings 7 and 8 into the position shown in Fig. 4 and temporarily retained in the elastic receiving receptacle 27 prior to the forward expelling movement of the piston 10.

In order to fire the arm, it is only necessary to pull rearwardly on the finger portion 28 of the trigger 22, thus releasing the downwardly projecting part 15 and permitting the spring 14 which is under compression to assume its expanded position and forcibly drive the piston 10 forwardly against the projectile and expelling it from the barrel of the arm. It will be noticed that the forward end of the magazine 3 is attached to the barrel 2 by means of the clip 29 which passes over the top of the magazine and down around the sides of and below the barrel 1, and it will also be noticed that the piston 10 when in the position shown in Fig. 2 prevents the projectiles from passing from the magazine into the barrel.

What I claim is:

1. In a toy gun designed to expel spherical projectiles and comprising, in combination, a barrel member, a magazine for containing said projectiles, and located above the barrel member, registering openings between the barrel and magazine to permit the foremost projectile to fall by gravity from the magazine into the barrel, an elastic receptacle located on the lower external side of the barrel and arranged in an opening thereof to temporarily retain a projectile in place prior to its expulsion, means comprising a pivotally mounted handle having an upwardly extending end for engaging a single

downwardly extending projection on the end of the expelling means for forcing the expelling means rearwardly a trigger engaging the projection to lock and release the expelling means whereby said projectile will be driven from the barrel as described.

2. In a toy gun of the magazine type and designed to expel spherical projectiles, a barrel, a stock secured to the barrel, a magazine secured to the stock and barrel in an inclined position and located above the barrel, registering openings between the forward portion of the magazine and the rearward portion of the barrel to permit the foremost projectile to pass from the magazine into the barrel by gravity, an elastic tongue formed with a curved portion to receive and temporarily retain said projectile in position prior to its expulsion from the barrel and located within an opening of the barrel, expelling means comprising a piston, a rod secured thereto, stops located near the rear end of the barrel, a compression spring located between the piston and said stops, the rear portion of the rod being formed with a downwardly projecting portion, a trigger, a setting lever for the piston designed to move the downwardly projecting portion of the rod to engage the trigger, means for locking the setting lever to the stock portion of the gun, whereby when the trigger is released said projectile will be expelled.
